UNITED STATES PATENT OFFICE.

BERTHOLD FRIEND, OF BROOKLYN, NEW YORK.

REMOVABLE LINING FOR CLOSETS AND THE LIKE.

Application filed November 1, 1926. Serial No. 145,637.

This invention relates to removable linings for clothes closets, storage compartments and other types of enclosures and has for its primary object to provide a novel and improved sectional structure which may be installed in a given area to protect garments or other merchandise and being an improvement over the subject matter described in my copending application, Serial No. 88,505, filed Feb. 15, 1926, for removable linings and fixtures for closets and the like.

One of the objects of my invention is to construct a lining preferably of cedar or other moth and germ proof material, preferably constructed in sections in such manner that they may be installed and set up within a given area, such as the interior of a clothes closet, linen closet, wardrobe, storage or display casing to protect the garments or merchandise from germs, dust or dampness.

A further object of my invention is to construct a sectional lining for closets and compartments generally which may be set up and installed without the aid of nails, screws, bolts, braces and other fastening or reinforcing elements and which may be easily disassembled and removed without damage.

Another object of my invention is to provide a lining of the character above specified consisting of standardized sections or panels constructed and arranged for assembly within the interior of a closet or compartment and spaced from the wall to prevent moisture or dampness from penetrating thereto and providing means for positioning said sections or panels irrespective of the closet wall surface.

A continued object of my invention is to provide a sectional lining for clothes closets and the like including a novel and improved means for supporting the sections or panels on the base board and in spaced relation from the floor and at the same time allow relative adjustment of the sections or panels to more accurately fit the closet area.

To enable others skilled in the art to more fully comprehend the underlying features and advantages of my construction that they may embody the same in the many uses and for the different purposes to which it is ca-

pable, drawings depicting a preferred form are annexed hereto as part of this specification in which

Fig. 1 is a view showing the panels when positioned on the base board and within a closet or compartment area.

Fig. 2 is a sectional view taken on the line 2—2 of Fig. 1.

Fig. 3 is a view showing a top shelf for the panels.

Fig. 4 is a view showing the bottom of the side and back panels.

Fig. 5 is a perspective view showing the means for supporting the panels on the back and side walls of the compartment.

Referring now to the drawings wherein like reference characters designate corresponding parts throughout the several views, 5 designates the bottom base board of a conventional type of clothes closet or compartment and 6 the side walls thereof, shown to illustrate but one application of the use of my invention since it is to be understood that the sections or panels may be installed in any other given area to protect clothing or other merchandise.

Within the closet or given area to be lined, I position a series of panels of predetermined dimensions according to the size of the closet comprising the rear wall panels 7, 8 and side wall panels 9, 10, each of which is provided with the usual type of battens 11. The inner edges of the rear wall panels 7, 8 are grooved at 12 throughout their length, being connected by the central spacing strip 13, which is T-shaped in cross section as shown by Figs. 2 and 4 of the drawing.

The rear and side wall panels are adapted to be maintained in parallelism and supported in uniform spaced relation from the walls of the closet or compartment and preferably on the baseboard and to that end, the bottom of each of the panels and central strip 13 are grooved at 13^a so as to interfit with the edge of an adjustable base rail. The base rail comprises the corner angle bars 14, 15 of light metal which are right angular in cross section but which may be bent and shaped to conform to any irregularity of the base board should the rear and side walls of the closet be disposed at other than right angles to each other. Connecting the

corner angle bars 14, 15 there is provided a connecting sleeve or light metal designated by numeral 16 which bridges the space between the inner ends of the corner angle bars so that they may be spread apart sufficiently to accommodate the desired length and be applicable for use in closets or compartments having different dimensions. It will be noted that the sleeve is bent at its edges 17, 18 to engage the top and bottom surfaces of the angle bars only so that the grooves in the bottom panels interfit therewith permitting their placement and adjustment. The side legs of the angle bars 15 are also provided with similar angular extensions 19, 20 to that of the sleeve so as to conform with the depth of the side walls of the closet and support the side panels.

Since the rear and side panels are preferably of the same dimensions and in order to permit the panels to be used in closets and compartments of different dimensions, I also provide edge strips 21, grooved at their bottoms to interfit with the angular extensions 19 and grooved along the edge to engage the edge of the side panel. The edge strips are held secure and clamped against the side panels by means of wedges.

The top of the rear wall and side wall panels are held in position by means of a top shelf 22 having at its bottom side a rear groove 23 adjacent its rear edge and side grooves 24 adjacent the sides thereof whereby said shelf may fit on the top of said panels. Similar grooves are formed in the top of the shelf whereby additional short panels and a second shelf (not shown) may be superposed thereon where it is desirable. The shelf is formed with a central, cut out portion 25 to permit the upper end of the central spacing strip 13 to enter and the front corners are further provided with cut out portions 26 for the upper ends of the edge strips 21, it being of course understood that the size and dimensions of the shelf will vary with the particular closet or compartment. Wedges 27 may be inserted between the rear and side walls and the edges of the shelf so as to lock the structure in spaced relation from the walls and to further prevent sagging of the panels. Suitable battens on the side panels or the rear wall panels or both may be provided to support hooks or other types of suspension means such as shown in my copending application above referred to.

It will thus be seen that having given a definite area or closet space to install the lining, the rear and side wall panels may be set up and supported on the base board by means of the corner angle bars, the connecting sleeve and extensions and assembled with the top shelf in spaced relation with the rear and side walls of the closet, being so positioned to be clamped or held by wedges to

prevent relative movement of the parts. In actual practice the panels are preferably constructed of light cedar wood or other moth and germ proof wood or the like which can be standardized so that if desired two or more panels may be employed for the rear wall or side walls depending upon the given area or enclosure. The construction is such that it is not necessarily a permanent one but on the other hand may be removed if so desired and again used in other instances and is therefore to be distinguished from what may be termed a fixture or part of a building operation. It is well known that the wall surface of a closet is frequently irregular, rough and very often damp because of its proximity to an outer wall. Consequently, in spacing the panels from the wall surface of the closet, an air space is provided preventing dampness from penetrating the panels and secondly by utilizing wedges, any irregularity of the wall surface is compensated for. Since the size or area of closet space is a determining factor in all installations, by utilizing a central strip and the edge strips for the side wall panels, said strips may be of such width, as to permit the panels to fit a definite area. It will further be observed that no fastening means of any nature is shown to maintain the corner angle bars and the connecting sleeve and side extensions on the base board. This is due to the fact of course that the weight of the panels and top shelf and the relative spacing of the panels so as to fit within a restricted area is such as to prevent the collapsing of the structure when set up either at the top or bottom particularly after the wedges are inserted in the space between the shelf, panels and walls of the enclosure.

From the above description and drawing the application of my invention, its use, installation and many advantages will be readily understood. While I have described my construction with some degree of particularity, I realize that many changes, modifications and alternative mechanical alterations may be made to suit particular circumstances. I therefore do not wish to be limited and restricted to the exact and specific details shown and described and reserve the right to modify the many details shown as to fall within the scope of the subject matter being claimed.

Having shown and described my invention what I claim as new is:

1. A lining for clothes closets and the like comprising a plurality of separable panels which may be constructed of moth or germ proof material such as cedar or its equivalent, said panels being arranged within and adjacent the rear and side walls of a given area, means for adjustably supporting said panels on the base board within said area and a top shelf cooperating with the upper

portions of said panels to maintain the same in parallelism to each other and in uniform spaced relation to the walls of said area.

2. A lining for clothes closets and the like comprising a plurality of separable panels which may be constructed of moth or germ proof material such as cedar or its equivalent, said panels being arranged within and adjacent the rear and side walls of a given area, a base rail adapted to be positioned on the base board of said closet, said panels having bottom grooves whereby they may be adjustably positioned on said base rail and a top shelf cooperating with the upper portions of said panels to maintain the same in parallelism to each other and in uniform spaced relation to the walls of said closet or area.

3. A lining for clothes closets and the like comprising a plurality of panels which may be constructed of moth or germ proof material such as cedar or its equivalent, said panels being arranged within and adjacent the rear and side walls of a given area, a base rail comprising corner angle bars and a connecting sleeve and side extensions adapted to be set on the base board of the closet or given area, said panels being grooved at their bottom and adapted to rest on the base rail and a top shelf cooperating with the upper portions of said panels to maintain the same in parallelism to each other and in uniform spaced relation to the walls of said closet or area.

35 4. A lining for clothes closets and the like comprising a plurality of separable panels which may be constructed of moth or germ proof material such as cedar or its equivalent, said panels being arranged within and adjacent the rear and side walls of a given area, means for adjusting a plurality of panels on the base board to fit within said

given area and a grooved shelf resting on the top of said panels to maintain the same in parallelism to each other.

45 5. A lining for clothes closets and the like comprising a plurality of separable panels which may be constructed of moth or germ proof material such as cedar or its equivalent, said panels being arranged within and in spaced relation to the rear and side walls of a given area, a central spacing strip between certain of the rear wall panels, edge strips cooperating with the side wall panels, said strips being arranged to produce a relatively close fitting structure within the given area, said panels and strips being grooved at the bottom, a base rail on which said panels and strips may be set and a top connecting shelf for said panels and strips for locking the same and maintaining them in uniform spaced relation to the walls of the given area.

55 6. A lining for clothes closets and the like comprising a plurality of panels which may be constructed of moth or germ proof material such as cedar or its equivalent, said panels being arranged within and in spaced relation to the rear and side walls of a given area, a central spacing strip between 60 certain of the rear wall panels, edge strips abutting certain of the side wall panels, said panels and strips having bottom grooves therein, a substantially U-shaped base rail 65 on which said panels and strips may be 70 relatively adjusted to fit within a given area and a grooved, top shelf resting on said panels, said strips being interlocked with the shelf and cooperating therewith to maintain the panels in uniform spaced relation 75 to the walls of the given area.

In testimony whereof I affix my signature.

BERTHOLD FRIEND.
